UNITED STATES PATENT OFFICE.

JOHN FLAMMANG, OF ST. LOUIS, MISSOURI, ASSIGNEE TO OTTMAR G. STARK, OF ST. LOUIS, MISSOURI.

PISTON.

1,351,239.

Specification of Letters Patent. Patented Aug. 31, 1920.

Application filed May 23, 1916. Serial No. 236,194.

To all whom it may concern:

Be it known that I, JOHN FLAMMANG, a citizen of the United States, residing at St. Louis, Missouri, have invented a new and useful Piston, of which the following is a specification:

This invention relates to pistons.

An object of the invention is to provide a piston devoid of piston rings or any other kind of packing and which, because of the inherent resiliency of the metal, presses closely against the cylinder wall and prevents the passage or escape of gas, steam or other piston operating agent, at the same time conforming to all requirements of efficient operation and having means for varying the extent of expansion of the piston.

Another object is to provide a piston of novel construction composed of a split expandable portion arranged to fit within a cylinder and press closely against the cylinder wall throughout its circumference and having a split top or head plate, and means for closing or sealing the space between the adjacent edges of the split head.

A general object of the invention is to provide an improved piston composed of an integral casting having a split head arranged to press closely against the cylinder wall during operation of the piston and to function properly and with a high degree of efficiency without the use of any kind of packing.

Various other objects and advantages will be apparent from a detailed description of the invention, reference being made to the accompanying drawing illustrating the piston in several stages of its construction, from the rough casting to the finished piston, in which—

Figure 1 is a view partly in section illustrating a casting having an integral top or head, from which the piston may be constructed.

Fig. 2 is a view illustrating the same casting after several stages of treatment.

Fig. 3 is a view of the piston casting having a wrist pin therein.

Fig. 4 is a side elevation of the casting after the portion above the wrist pin has been placed under tension and a key or closure has been placed in connection with the piston to close the opening through the top or head thereof.

Fig. 5 is a side elevation of the finished piston ready to be placed in the cylinder.

Fig. 6 is a view partly in section showing the piston mounted in a cylinder.

Fig. 7 is a detailed view illustrating a feature of the invention.

The casting from which the piston is made includes a lower ring 1, an upper ring 2, a number of connections 3 integrally uniting the lower and upper rings, and a top or head 4 integral with and closing the opening of the upper ring. The connections 3 are formed with inwardly extending bosses 5 through which the holes for the wrist pin are formed, and the top or head plate is provided with a pair of spaced projections 6.

The head or top plate and the upper ring are then cut transversely as shown at 7 (Fig. 2) and inwardly and downwardly inclined holes 8 are formed through the connections 3 and the bosses 5. The piston body may also be tapered if desired, the original shape being indicated by the dotted lines in Fig. 2.

Next the connections 3 are pressed apart in order to separate farther the segmental portions of the upper ring 2 and the top or head of the piston. This may be done in any any desired manner, though in the construction illustrated it is effected by forcing a wrist pin 9 into the inclined holes 8, the result being that due to the inclination of the holes the wrist pin forces and holds the connections 3 apart. The wrist pin is securely held by set screws 10 passing through the bosses and engaging the wrist pin as shown in Fig. 3.

The head or top plate of the piston is formed with a transverse groove or channel in which a key or closure 11 is seated. The side walls of the groove or channel are formed obliquely so that the lower portion of the groove or channel is wider than its upper portion, and the key or plate 11 is similarly shaped so that when the piston is under compression within the cylinder for which it is intended, the key or plate will be held from working out of the groove or channel in which it is placed. The key or plate 11 extends across the space 7 and forms a seal to prevent the passage of steam, gas or other operating agent through said space when the piston is in operation. The key 11 extends entirely across the top or head of the piston so that the longitudinal

movement thereof is prevented by the walls of the cylinder. Coöperating keys 12 are preferably seated in appropriate grooves below the key 11, but said keys 12 may be omitted if desired. In case the keys 12 are used there will be one at each side of the piston, said keys 12 being in the form of narrow plates seated in grooves in the piston and being held from displacement by 10 the cylinder wall when the piston is operating.

The piston above the wrist pin is finished in such manner that it will press closely against the cylinder wall and form such 15 close contact as to render unnecessary the use of piston rings or packing.

In the construction of the piston a bolt 13 is passed through holes in the projections 6 and the nut 14 on the bolt is turned until 20 the connections 3, above the wrist pin, are bent or placed under tension, the segmental sections of the upper part of the piston being drawn to the positions which they occupy when the ring is under compression 25 in a cylinder. While the piston is thus held under tension it is finished, the finished outlines of the piston being indicated by dotted lines 15 (Fig. 4) by reference to which it will be observed that the upper ring 2 is 30 left of slightly larger diameter than the lower portion of the piston. In its finished shape the lower portion of the piston is of slightly less diameter than the diameter of the cylinder for which it is intended, while 35 the upper portion of the piston while under compression is of the same diameter as the diameter of the cylinder in which the piston is intended to operate. The lower ring 1 of the piston may also be formed with a number 40 of circumferential oil grooves 16 for containing lubricant that will be applied to the wall of the cylinder during operation of the piston therein.

After the piston has been finished the nut 45 14 is turned back to permit the upper portion of the piston to expand so that when the piston is applied within a cylinder the resiliency of the metal will cause the upper portion of the piston to press closely against 50 the cylinder wall all around. The nut 14 may be held from turning on the bolt by any device suitable for that purpose as, for instance, by a plate spring 17 engaging in a 55 groove or recess in the top plate of the piston and bearing against one of the side walls of the nut. By accurate adjustment of the nut on the bolt part of the expansive force of the upper portion of the piston may be relieved from the cylinder wall. This may 60 be effected by turning the nut on the bolt to position so as to limit the extent of expansion of the upper portion of the piston.

As shown in Fig. 6, the upper edge of the ring 1 is beveled to provide a scraping edge 65 18 and the lower edge of the ring 2 is bevel-

ed to provide a scraping edge 19. The scrapers 18 and 19 during operation of the piston scrape the oil from the cylinder wall.

In Fig. 6 the connecting rod 20 is illustrated in connection with the wrist pin 9. 70

I claim:

1. A piston, having a body composed of an upper portion, a lower portion, and resilient members integrally uniting the upper portion with the lower portion and being 75 tensioned to press the upper portion outwardly against the wall of the cylinder in which the piston is mounted; and a head integral with the upper portion.

2. A piston, composed of a number of segmental sections, a head integral with said sections, and resilient members integral with said sections for pressing said sections outwardly against the wall of the cylinder in which the piston is mounted. 80

3. A piston, composed of a body whose upper portion comprises a number of segmental sections and which upper portion is of larger diameter than the lower portion of the piston body, a head integral with the segmental sections of the upper portion of the body, and resilient members for pressing the segmental sections against the wall of the cylinder in which the piston is mounted. 85

4. A piston, comprising a hollow body whose upper portion consists of a number of segmental sections and which upper portion is of larger diameter than the diameter of the lower portion of the piston body, resilient members for pressing the segmental sections of the upper portion of the piston body outwardly against the wall of the cylinder in which the piston is mounted, a head integral with the segmental sections 100 of the piston body, and means for limiting the extent of expansion of the upper portion of the piston. 105

5. A piston, comprising a hollow body having an upper portion composed of a 110 number of segmental sections, a head comprising sections integral with said segmental sections respectively, resilient members for pressing the segmental sections outwardly against the wall of the cylinder in which the piston is mounted, and means for preventing the passage of gas between the sections of the head. 115

6. A piston, comprising a hollow body whose upper portion is divided into segmental sections which are expansible from and compressible toward each other, and which when compressed toward each other are of the same diameter as the diameter of the cylinder for which the piston is intended; a head divided into sections which are integral with said segmental sections respectively and which move with the segmental sections during expansion and compression thereof, and resilient members for 120 125 130

pressing the segmental sections outwardly against the wall of the cylinder in which the piston is mounted.

7. A piston, comprising a hollow body whose upper portion is divided into segmental sections which are expansible from and compressible toward each other, and which when compressed toward each other are of the same diameter as the diameter of the cylinder for which the piston is intended; a head divided into sections which are integral with said segmental sections respectively and which move with said segmental sections during expansion and compression thereof; resilient elements for pressing said segmental sections outwardly against the wall of the cylinder; and a device for preventing the passage of gas between the sections of the head.

8. A piston, comprising a hollow body whose upper portion is divided into segmental sections which are expansible from and compressible toward each other, and which when compressed toward each other are of the same diameter as the diameter of the cylinder for which the piston is intended; a head divided into sections which are integral with said segmental sections respectively and which move with said segmental sections during expansion and compression thereof; resilient elements for pressing said segmental sections outwardly against the wall of the cylinder; a device for preventing the passage of gas between the sections of the head; and means for preventing the passage of gas between the segmental sections.

9. A piston, comprising a hollow body whose upper portion is divided into segmental sections which are expansible from and compressible toward each other, and which when compressed toward each other are of the same diameter as the diameter of the cylinder for which the piston is intended; a head divided into sections which are integral with said segmental sections respectively and which move with said segmental sections during expansion and compression thereof; resilient elements for pressing said segmental sections outwardly against the wall of the cylinder; a device for preventing the passage of gas between the sections of the head; and a wrist pin supported by said resilient members.

10. A piston, comprising a hollow body whose upper portion is divided into segmental sections, a piston head divided into sections which are integral with said segmental sections respectively, an element supported by said head preventing the passage of gas between the sections of the head, re-

silient members for pressing said segmental sections outwardly against the wall of the cylinder in which the piston is mounted, and a wrist pin in connection with said members holding said members under tension to cause said members to press said segmental sections outwardly.

11. A piston comprising a hollow body whose upper portion is divided into compressible and expansible segmental sections which, when compressed are of the same diameter as the diameter of the cylinder for which the piston is intended and which when expanded are of a diameter in excess of the diameter of the cylinder for which the piston is intended; the piston being compressible into the cylinder whereby the material of the segmental section is placed under tension; a segmental top plate in connection with the piston; and means for preventing the passage of the gas between the sections of the top plate.

12. A piston comprising a body composed of a lower ring, an upper ring divided into segmental sections which when compressed toward each other are of the same diameter as the diameter of the cylinder for which the piston is intended and which when expanded from each other are of larger diameter than the diameter of the cylinder for which the piston is intended; a segmental top plate integral with said segmental sections; connections integrally uniting the segmental sections with the lower ring; and devices preventing the passage of gas between the segmental sections of the top plate.

13. A piston comprising a body composed of a lower ring, an upper ring divided into segmental sections capable of expansion and compression, and means limiting the expansion of the segmental sections of the upper ring.

14. A piston comprising a body composed of a lower ring, an upper ring divided into segmental sections capable of expansion from and compression toward each other; a top plate divided into segmental sections integral with the segmental sections of the upper ring; and means limiting expansion of the upper ring.

15. A piston, comprising a number of segmental sections arranged to press against the cylinder wall by the resiliency of the material of said sections, a head integral with said sections, and resilient members integral with said sections coöperating with said sections to press the sections outwardly against the wall of the cylinder.

JOHN FLAMMANG.
